DESIGN FOR A STATUETTE

Donn Briner, Chicago, Ill.

Application November 23, 1935, Serial No. 59,717

Term of patent 14 years

To all whom it may concern:

Be it known that I, Donn Briner, a citizen of the United States, residing at Chicago, in the county of Cook and State of Illinois, have invented a new, original, and ornamental Design for a Statuette, of which the following is a specification, reference being had to the accompanying drawing, forming part thereof.

Fig. 1 is a side view of a statuette embodying my new design.

Fig. 2 is a front view of the same statuette embodying my new design.

I claim:

The ornamental design for a statuette, as shown,

DONN BRINER.
